GRINDING METHOD

Howard W. Meyer, Indianapolis, Ind., assignor, by
mesne assignments, to The Marquette Metal
Products Company, Cleveland, Ohio, a corpora-
tion of Ohio

Application April 9, 1948, Serial No. 19,972

4 Claims. (Cl. 51—289)

1

The present invention is concerned with a means and method for finishing the outer diameter of certain members of an assembled group of parts on a lathe or grinding machine.

In the manufacture of a spring clutch assembly incorporating a sleeve or hub member on which is mounted a clutch spring and a pair of flanking bearing members, difficulty has been encountered in maintaining the necessary tolerances and concentricity in the unit after assembly. When the separate parts of the assembly are finished before being assembled, the unit may reflect an accumulation of tolerances, allowable so far as the individual parts are concerned, but resulting in undesirable relative eccentricity of parts or sub-assemblies in the finished unit. Heretofore it was considered impracticable to grind the bearing surfaces after assembly of the unit, since some of the coils of the spring incorporated therein had a larger outer diameter than the bearing surfaces to be finished and further the spring was free-floating radially about the hub or sleeve member so that it would necessarily be in the way of a grinding or cutting tool as well as suffer possible damage to its finished surface were such an operation attempted.

An object of the present invention is to provide an apparatus or fixture for supporting such an assembly during the finishing operation which will be adapted for use with a grinding machine or lathe, such as a Landis grinder or lathe, and will hold the spring out of the way of the grinding or cutting tool while enabling efficient finishing of the bearing surfaces after assembly and the maintenance of necessary finished tolerances.

A further object of the invention is to provide a fixture as described above which may be inexpensively and easily fabricated and in use will facilitate such operation as outlined above, requiring a minimum of time and labor.

Another object is to provide a method for grinding or cutting a surface on a plural assembly as described which will provide a finished surface of required concentricity within required tolerances while saving both labor and time.

In the drawing, Fig. 1 is a side elevation of the fixture employed for practicing the invention; Fig. 2 is a side elevation of an assembly such as the method and fixture of the present invention is designed to handle; Fig. 3 is a diagrammatic view showing the plural assembly mounted in the fixture for the finishing operation.

2

With reference to the drawing, the fixture comprises a bed plate 1 to which vertical standards or brackets 2, 10 and 20 are rigidly attached in a common vertical plane. A generally horizontal arm 3 is pivoted at 4 to the top end of the largest bracket 2. A free turning roller 5 is mounted at the free end of arm 3 for engaging one portion of the work constituted by the spring clutch assembly. A rod 6 extends through the arm 3 between its ends, depends therefrom and has a spring 7 bearing downwardly on the arm and holding the arm against a shoulder 8 on the rod below the arm. The vertical bracket 10 has a free turning roller 11 mounted on its upper free end. A horizontal arm 12 extends rigidly from the bracket 10 and is screw-threaded for receiving companion threads on the lower end of rod 6. The third vertical bracket 20 has a free turning roller 21 mounted on its upper end. All the rollers are also in a common vertical plane.

Arm 3 may be swung vertically, within the limits of the spring-biased connection 7, 8 to move roller 5 with reference to the position of 25 the fixed rollers 11 and 21 to allow the work to be moved into place in engagement with the three rollers. The normal position of roller 5 may be adjusted through the threaded connection of rod 6 with member 12, to control the pressure 30 of roller 5 on the work and allow for variation in the diametral size of the work.

As an example of the type of work for which the present method and means was devised, a spring clutch helix assembly is illustrated in 35 Fig. 2. This assembly comprises a hub or sleeve A having a circular flange B formed thereon, the inner axially disposed face thereof being of helical form complementary to the adjacent end of a helical clutch spring C. The spring is connected to flange B by means of a toe C' on the spring engaging a radial slot in the flange. Bushings or bearing members D are concentrically mounted on sleeve A at its ends. The spring C has a materially larger inner diameter than the outer diameter of sleeve A so that it is substantially in a radially free-floating condition, loosely around the sleeve A.

The assembly described above is intended for insertion within an axial bore of a gear indicated in broken lines at G in Fig. 2 for free rotation relative thereto in one direction. Sleeve A is secured to a shaft whereby torque may be transmitted from the gear to the shaft through the spring clutch assembly. The outer peripheral surface of the spring is designed for grip-

ping frictional engagement with the drum surface formed by the axial bore of the gear whenever the gear is turned in its normal driving direction. Since the device is intended for high speed operation, all the parts thereof must be finished to close tolerances and concentricity of the bearing surfaces between members D and the gear member is necessary to prevent vibration and other undesirable conditions.

To satisfy the requirements mentioned above it is desirable that the surfaces of bearing members D be ground or finished at the same time and while mounted on the helix sleeve A and after the unit is thus assembled so that the inner diameter of the hub or sleeve A will be exactly concentric with the outer diameter or bearing surface of the members D. Since some of the coils, energizing coils E, of spring C have a larger outer diameter when relaxed than the outer diameter of the bearings D and the entire clutch spring is loosely mounted on sleeve A between the projecting bearings, performance of such an operation by the usual methods would be impossible without doing damage to the accurately machined clutching surface of the spring.

When the peripheral surfaces of the helix assembly are to be ground on a grinding machine, sleeve A with spring C and bearing members D assembled thereon, is mounted on an arbor 39 (Fig. 3) of the same diameter as the shaft on which the assembly is finally to be mounted. The arbor is then secured in centers supported on a traversing carriage for movement parallel to the axis of the grinding wheel movable for cross-feed movement in a direction at right angles to the carriage traversing movement for determining the radial dimension of the finished surface. The fixture 1 etc. of this invention is mounted on the movable carriage in fixed relation to the center supporting arbor 39 and in such position that its rollers 5, 11 and 21 will make three-region contact with spring C, as shown diagrammatically in Fig. 3. Arm 3 and roller 5 may be retracted, as by hand, while the assembly A through E is being located on the arbor 39 and its supporting centers, rollers 11 and 21 supportingly engaging the periphery of spring C between the members D and out of contact therewith. Release of arm 3 brings roller 5 into contact with the periphery of the spring. All of the rollers being of a width somewhat less than the total length of spring C, they will enter between the members D to urge the inner surface of the spring toward or against the periphery of sleeve A.

The fixture with its rollers is so arranged and mounted upon the traversing carriage that the axis of the spring engaged by the rollers, i. e. the center of the circle defined by the three rollers, is eccentric of the center of the axis or center of sleeve A or in other words of the axis of the arbor upon which the sleeve is mounted and its supporting centers. By thus supporting the spring eccentrically of the bearing members D being worked upon, the surface region of the spring adjacent the grinding wheel is progressively held in spaced relation to the surface of the bearings at the point where the working tool contacts.

As is customary in grinding machines of this type, the arbor 39 is rotated on its supporting centers for finishing the circumferential surface of the bearing members D. If the inner surface of the main coil of the spring is held against the surface of sleeve A in the opposite direction from the working tool, it will also be rotated eccentrically of the bearings and with its outer peripheral surface clear of the grinding wheel. The traversing carriage is moved to bring first one and then the other of the members D into contact with the grinding wheel, which is moved at right angles thereto for grinding the surfaces to the proper radial dimension, all in the usual approved manner, so that the surfaces of the members D may be precision finished within allowable tolerances and concentrically of the bore of sleeve A after final assembly, with the same precision and facility as would be possible if the spring were not mounted on the assembly, and without damage to the spring's surface.

trically of the bearings and with its outer peripheral surface clear of the grinding wheel. The traversing carriage is moved to bring first one and then the other of the members D into contact with the grinding wheel, which is moved at right angles thereto for grinding the surfaces to the proper radial dimension, all in the usual approved manner, so that the surfaces of the members D may be precision finished within allowable tolerances and concentrically of the bore of sleeve A after final assembly, with the same precision and facility as would be possible if the spring were not mounted on the assembly, and without damage to the spring's surface.

The method and means described above may be employed for finishing various assemblies where a similar problem is presented. In some cases the tubular member corresponding to the spring C, E may be free to rotate relative to the inner supporting member, in which case the rollers may be replaced by non-rotating engaging members and the inner body allowed to rotate within and independently of the tubular member so engaged.

I claim:

1. In peripherally machining one of two permanently loose-coupled but normally concentric circular parts the method of protecting the other part against damage by a tool comprising supporting such one part on a fixed center for presentation to the tool and supportingly engaging the periphery of other part at opposite sides of the region of operation of the tool and at regions spaced apart circumferentially of said other part, the regions of engagement being so located as to maintain said other part continuously eccentric relative to said one part.

2. The method of machining the peripheral surface of a protruding flange member on a generally circular body forming a part of a plural assembly including a tubular member carried permanently but loosely on said body adjacent said flange member, comprising mounting said body on a fixed axis for rotatably presenting the surface to be machined to a machining tool, and meanwhile engaging the surface of said tubular member at a plurality of circumferentially spaced regions around its periphery and so located as to hold the axis of the tubular member eccentrically of the body to be machined in a direction away from the region of operation of said tool.

3. The method of machining the peripheral surfaces of protruding flange members carried by a generally cylindrical body forming a part of a plural assembly including a tubular member freely mounted on said body between said flange members and having an outer diameter at least as great as that of the surface to be machined, comprising mounting said body on a fixed axis for rotatably presenting the surfaces to be machined to a machining tool, engaging the surface of said freely mounted tubular member at spaced regions about its periphery so located that the tubular member is maintained eccentrically of said fixed axis in a direction away from the point of engagement of said tool with the surface to be machined, and effecting rotation of said body within said tubular member.

4. The method of machining the peripheral surfaces of protruding flange members carried by a generally cylindrical body forming a part of a plural assembly including a tubular member freely mounted on said body between said flange members, comprising mounting said body upon a rotatable arbor positioned to present the sur-

face of the flange members carried thereby to a machining tool, engaging the peripheral surface of said freely mounted tubular member by fixed rollers positioned at intervals about its periphery, said rollers being located with the center of the circle defined thereby eccentrically offset with respect to the axis of said rotatable arbor in a direction opposite the point of engagement of said surface and said machining tool, whereby said cylindrical body and said tubular member will rotate together and on eccentric axes so that the surface of said flange members and the surface of said tubular member will be offset at said point of engagement.
